UNITED STATES PATENT OFFICE

ALEX M. MCLENDON, OF SAVANNAH, GEORGIA, ASSIGNOR OF ONE-THIRD TO A. P. SOLOMON, JR., AND ONE-THIRD TO A. L. HILDRETH, BOTH OF SAVANNAH, GEORGIA

COLLAR PRESSING MACHINE

Application filed June 26, 1930. Serial No. 463,987.

This invention relates to a laundry appliance for pressing collars, and it has more particular reference to a miniature machine of this class which is expressly designed for folding and pressing starched collars of the semi-soft and stiff types and generally referred to in the trade as detachable collars and primarily used on shirts for masculine wear.

The inventive conception is embodied in a structure which is primarily characterized by a horseshoe shaped form and a substantially U-shaped channelled pressing head.

In accordance with the conception, I provide an electrically heated pressing head and a motor actuated operating device for moving the head intermittently toward and from the form, whereby to permit the collars to be successively placed in position and removed during the interval of movement of the operating device for said head.

It is my primary aim to generally improve upon electric heated and operated mandrels by providing a structure which is characterized by simplicity in construction, economy in manufacture and sale, and efficiency in operation.

In the drawings:

Figure 1 is a side elevational view showing the complete mandrel as developed in accordance with the invention.

Figure 2 is an end view thereof observing the structure in a direction from right to left in Figure 1.

Figure 3 is a top plan view of the same.

Figure 4 is an enlarged detail cross section on the line 4-4 of Figure 2.

Figure 5 is a detail section on the line 5-5 of Figure 4.

The relatively stationary part or stand is designated generally by the numeral 6. This comprises supporting legs 7 appropriately fastened as at 8 to a stationary support 9 such as a table or the like. The stand embodies a horseshoe-shaped form 10 whose upper edge is rounded off as at 11 in Figure 4, to prevent cutting of the upper edge of the collar when a collar is placed over the form and this rounded upper edge of the form also gives the upper edge of the collar

a rounded shape when the collar is acted on by the head, now to be described.

The relatively swingable electrically heated head is generally represented by the numeral 12. This head is also of substantially horse shoe shape and is substantially inverted U-shaped in cross section so as to fit over the form 10 and the collar thereon as shown in Figure 4. The wall portions of the channel straddle the form as shown. This part 12 is of hollow construction and provided with internal electric heating means 13 of appropriate construction. Thus, this part 12 functions as an iron.

The head is manipulated through the medium of an appropriate operating device generally denoted by the numeral 14. This comprises an arm portion 15 having a plurality of fingers 16 17 and 18 attached through the medium of coiled springs 19 to the adjacent portions of the channel head.

The lower end portion of the curvate arm 15 is pivotally attached as at 20 on the base plate 21 of the electric motor 22. The shaft of the motor is provided with an eccentric or cam 23 operable within a frame 24 attached to the lower end of the arm 15. Under this arrangement, the cam co-acting elements 23 and 24 serve to rock the device 14 toward and from the stand 6, thus alternately moving the head to and from its operating position.

The cam 23 is so formed and positioned in the frame 24 that during the operation of the cam 23 by the motor the head or iron will remain on the form 10 and the collar thereon for a period of a few seconds and then the head is raised so that the ironed collar can be removed from the form and a new one placed on the form while the head is being moved away and towards the form as shown in dotted lines in Figure 1. The springs 19 act to permit the head to remain stationary on the collar on the form for a short time while the arm 15 is still being moved forwardly by the cam, and then the direction of motion is reversed and the arm 15 and the head swing upwardly to the dotted line position shown in Figure 1.

The device constitutes a simplified and

practical means for smoothing the edge or crown portion of the fold of a starched collar.

It is thought that persons skilled in the art to which the invention relates will be able to obtain a clear understanding of the invention after considering the description in connection with the drawings. Therefore, a more lengthy description is regarded as unnecessary.

10 Minor changes in shape, size, and rearrangement of details coming within the field of invention claimed may be resorted to in actual practice if desired.

I claim:

15 In a collar pressing machine of the class described, a motor including a stationary base, a stand supported adjacent said base and including a form, a pressing head co-operable with said form, a carrier comprising an arm pivotally attached at its lower end to said base, outwardly extending fingers on the upper end of the arm, springs connecting the extremity of each finger to the head, a frame carried by the pivoted end portion of the arm, and an eccentric cam on the motor shaft confined within said frame for swinging the arm and head toward and away from the stand.

In testimony whereof I affix my signature.

30 ALEX M. McLENDON.
